CLAIM

The ornamental design of a standard aircraft master log with master document locator, as shown and described.

DESCRIPTION

FIG. 1 is panel one of the standard aircraft master log with master document locator, shown separately for ease of illustration;

FIG. 2 is panel two of the standard aircraft master log with master document locator, shown separately for ease of illustration;

FIG. 3 is panel three of the standard aircraft master log with master document locator, shown separately for ease of illustration;

FIG. 4 is panel four of the standard aircraft master log with master document locator, shown separately for ease of illustration;

FIG. 5 is panel five of the standard aircraft master log with master document locator, shown separately for ease of illustration;

FIG. 6 is panel six of the standard aircraft master log with master document locator, shown separately for ease of illustration;

FIG. 7 is panel seven of the standard aircraft master log with master document locator, shown separately for ease of illustration;

FIG. 8 is panel eight of the standard aircraft master log with master document locator, shown separately for ease of illustration;

FIG. 9 is panel nine of the standard aircraft master log with master document locator, shown separately for ease of illustration;

FIG. 10 is panel ten of the standard aircraft master log with master document locator, shown separately for ease of illustration;

FIG. 11 is panel 11 of the standard aircraft master log with master document locator, shown separately for ease of illustration;

FIG. 12 is panel twelve of the standard aircraft master log with master document locator, shown separately for ease of illustration; and,

FIG. 13 is panel thirteen of the standard aircraft master log with master document locator, shown separately for ease of illustration.

The broken lines in each view represent the bounds of a portion of the standard aircraft master log and form no part of the claimed design.

The Standard Aircraft Master Log with Master Document Locator is a logbook of conventional thickness and size.

The “Aircraft Cockpit and Globe” logo trademark/service mark forming part of the claimed design are registered trademark/service marks belonging to Dr. Eric Kudimi.
